CLAIM

The ornamental design for a turntable for use in microwave ovens, as shown.

DESCRIPTION

FIG. 1 is an isometric view of a turntable for use in microwave ovens showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right-side elevational view thereof; and

FIG. 7 is a bottom plan view thereof.
